UNITED STATES PATENT OFFICE

HERBERT C. DRUMM AND JOHN M. CALLAHAN, OF CANTON, OHIO, ASSIGNEES TO THE UNION METAL MANUFACTURING COMPANY, OF CANTON, OHIO, A CORPORATION OF OHIO

METAL BUILDING

Application filed April 1, 1926. Serial No. 99,000.

The invention relates to sheet metal buildings and particularly to buildings adapted to be used for gasoline filling stations and the like.

5 The object of the improvement is to provide a sheet metal building of this character in which the whole structure is mounted upon a foundation and supported by columns located at the corners of the building, angular covers being provided for the columns upon the interior of the building; metal beams or other structural or ornamental members being attached by means of tie-rods extending through the columns to an anchor bolt in the concrete base upon which the sill is mounted; to provide a reinforced sheet metal sill having a structural channel member attached to lugs cast integral with the column base providing a rigid framework 20 for the attaching of intermediate upright stud members, panels and sash; to provide hollow sheet metal panels and hollow sheet metal studs to which the panels are connected providing air spaces in the walls of the building; to provide weather strips to cover the edges of the panels and arranged to be attached to the studs; and to generally improve and simplify the construction of sheet metal buildings.

30 An embodiment of the invention thus set forth in general terms is illustrated in the accompanying drawings, in which

Figure 1 is a perspective view, with parts broken away, of a sheet metal building constructed in accordance with the invention;

Fig. 2, a vertical sectional view through one of the corner columns and a portion of the roof truss structure;

Fig. 3, a section through the cornice and roof structure;

Fig. 4, a horizontal sectional view through one wall and a corner portion of the building;

Fig. 5, a vertical sectional view through one wall showing the sill and cornice structure;

Fig. 6, a detached perspective view of one corner column and the associated parts.

Similar numerals indicate corresponding parts throughout the drawings.

The building is designed for use as a gaso-line filling station or the like and is adapted to be erected upon a base 1, of cement or the like, of substantially the size and shape of the plan of the building.

55 An anchor bolt 2 is arranged to be imbedded in each cornice portion of the cement base and provided with a threaded coupling 3 extended up through the surface of the cement.

An column 4 which may be a fluted tubular sheet metal column is mounted at each corner of the building to support the same. Each of these columns is arranged to be mounted upon a cast base 5 axially located over the anchor bolt at each corner portion of the foundation. If desired this cast base may be made of two pieces, the cast ring portion 5^a being mounted upon the annular flange 5^b of the base proper and provided with an annular flange 6 at its upper side over which the lower flanged end of the sheet metal column is fitted as best shown in Fig. 2.

A cap is mounted upon the upper end of each sheet metal column 4, and each cap may consist of a cast ring 7 provided with a flange 8, extended into the upper flanged end of the sheet metal column and arranged to fit upon the annular flange 9 upon the square castings 10. Lattice girders or I-beams 11 are mounted upon the square caps 10 having the flanged perforated end portions 12 which receive the upper ends of the tie-bolts 13, connected at their lower ends to the couplings 3. A nut and washer 15 and 16 respectively may be 80 mounted upon the upper threaded end of each tie-rod to secure the girders, caps, columns or base tightly in position upon the cement foundation.

85 Each girder is surrounded by a substantially rectangular sheet metal beam 17 which is provided not only for ornamental reasons but also as a means for attaching the upper ends of the studding as will be later described, the under side of each of these sheet metal beams being provided with a longitudinal pressed rib 18.

Structural channel sills 19 are mounted upon the cement foundation and extended between the corner columns, being arranged to 100

fit over the lugs 20 formed upon the cast base 5.

The studs 21, preferably of cross sectional T-shape, are located between the sills 19 and beams 17, being provided at their upper and lower ends with the channel groove 22 arranged to receive the depending rib 18 upon the beam and the rib 23 formed upon the sheet metal sill covering 24. These studs may be 10 fastened in place by bolts, screws, welding or the like, being located at specified spaced points.

The lower portion of the walls of the building is preferably formed of panels 25 formed 15 of spaced sheet metal walls each panel being provided at its lower edge with the depending flange 26 for engagement with the rib 23 upon the sill cover.

The upper edge of each of these panels is 20 preferably provided upon its outer side with an inclined rectangular window sill portion 27.

The upper portion of each side wall may be formed of sashes 28 provided with glass 25 panes 29. Each of these sashes is provided 25 at its lower edge with the angle strip 30 for engagement over the upper edge of the adjacent panel, at its upper edge with a similar angle strip 31 for engagement with the depending rib 18 of the beam.

Each of the studs is covered by means of a hollow channel weather strip 33 which may be attached to the stud by means of screws or the like covering the joint between each 35 stud and the adjacent panels and sashes and not only closing the joint but also giving the building a finished appearance.

The side edges of the panels and sashes are provided with flange joints 35 which form 40 permanent closures for the panels and which extend across the base portions of the studs and are received between the studs and the channel cover strips 33 as illustrated in Fig. 4.

Each interior corner of the building is provided with an angular sheet metal member 45 36 having the flanged edges 37 arranged to be extended between the adjacent studs and weather strips as shown in Fig. 4, thus covering the portion of the column exposed to 50 the interior of the building.

A roof truss 38 is bolted or otherwise connected upon the upper edges of the girders 11 at the front and rear sides of the building and any suitable roof structure may be built 55 thereon. For the purpose of giving the building a pleasing appearance an ornamental sheet metal cornice 39 may be connected to the end portions of the roof trusses and to the sheet metal beams 17 as by the flange 40 60 extended into the channel groove 41 of the beam.

We claim:

1. A sheet metal building including uprights, and hollow metal panels, located 65 between said uprights, said panels having

flanged joints at their edges forming permanent closures for the hollow panels, and means connecting said flanges and said uprights.

2. A sheet metal building including hollow uprights, and hollow metal panels, located between said uprights, said panels having flanged joints at their edges forming permanent closures for the hollow panels, and means connecting said flanges and said uprights.

3. A sheet metal building including sills at its lower portion, beams at its upper portion, upright T-shaped studs connected at their ends to the beams and sills, panels having flanges at their side edges extended over said studs, and weather strips connected to the studs and engaging said flanges, whereby the inner surfaces of the panels and strips are flush.

4. In sheet metal building construction including columns and girders supported on the columns, the combination of hollow beams adapted to cover the girders, said hollow beams having depending longitudinal ribs, sills adapted to extend between the columns below said beams, studs provided with channel ends engaging said ribs and sills, panels supported upon said sills and located between said studs, and means connecting the panels and studs.

5. In sheet metal building construction including columns and girders supported on the columns, the combination of hollow beams adapted to cover the girders, said hollow beams having depending longitudinal ribs, sills adapted to extend between the columns below said beams, studs provided with channel ends engaging said ribs and sills, panels supported upon said sills and located between said studs, means connecting the panels and studs, and sheet metal cornices connected to said hollow beams.

6. In sheet metal building construction including columns and girders supported on the columns, the combination of hollow beams adapted to cover the girders, said hollow beams having depending longitudinal ribs, sills adapted to extend between the columns below said beams, hollow T-shaped studs provided with channel ends engaging said ribs and sills, and hollow panels of substantially the same thickness as the T-shaped studs provided with reduced flanges at their side edges overlapping said studs and supported upon said sills, and channel weather strips engaging said flanges and connected to the studs.

In testimony that we claim the above, we have hereunto subscribed our names.

HERBERT C. DRUMM.
JOHN M. CALLAHAN.
